UNITED STATES PATENT OFFICE.

HENRY PRICE BALL, OF NEW YORK, N. Y., ASSIGNOR TO GENERAL INCANDESCENT ARC LIGHT COMPANY, OF NEW YORK, A CORPORATION.

HIGH-TENSION OIL-SWITCH.

SPECIFICATION forming part of Letters Patent No. 760,601, dated May 24, 1904.

Application filed February 25, 1902. Serial No. 95,609. (No model.)

To all whom it may concern:

Be it known that I, HENRY PRICE BALL, a citizen of the United States, residing at New York city, county and State of New York, have invented certain new and useful Improvements in High-Tension Oil-Switches, of which the following is a specification.

My invention relates to oil-switches of the type especially designed for use with circuits transmitting high-tension large-quantity currents—such, for instance, as a six-thousand-volt three-phase current.

My invention consists in the construction of the switch and in the means for electrically operating the switch from a distance.

The general object of my invention may be stated to be the construction of a switch for safely handling high-tension large-quantity currents and which under ordinary conditions of service will not be injuriously affected by the arc produced upon breaking the circuit or if injured by an excess of arc may be readily and quickly repaired.

A further object of my invention is to provide mechanism for operating the switch, which may be energized through the instrumentality of simple electromechanical means located at a distance.

The accompanying drawings will serve to illustrate my invention, and in which similar letters and numerals indicate like parts.

Figures 1, 2, and 3 are diagrams illustrating the circuit connections between the mechanism for operating my improved oil-switch and electromechanical means for energizing the operating mechanism and also showing the successive positions of the parts. Fig. 4 is a front elevation of the oil-switch and its actuating mechanism. Fig. 5 is a side elevation taken on the line X X of Fig. 4. Fig. 6 is a vertical section through one of the magnets of the actuating mechanism and its dashpot. Fig. 7 is a longitudinal section through the left-hand upper joint of the movable support for the oil-wells. Fig. 8 is a vertical section through one of the oil-wells with one of the bridge-rods in a closed position. Fig. 9 is a vertical section through the guide, cap, and insulator and shows one of the bridge-

rods in the open position. Figs. 10 and 11 are transverse sections taken, respectively, on lines Y Y and Z Z of Fig. 8. Fig. 12 is a plan view of the contact-block and upper row of contact-springs. Fig. 13 is a front elevation of the actuating mechanism for the switch and shows such mechanism in its first position. Fig. 14 is a similar view showing such mechanism in its second position. Fig. 15 is a top view of that portion of the actuating mechanism which is located back of the supporting-standard. Fig. 16 is a front view showing the relation of one of the levers to the locks. Fig. 17 is a side elevation of the actuating mechanism.

Referring to the drawings, Figs. 1, 2, and 3 illustrate diagrammatically the general relation existing between the main distributing system, the oil-switch, and its energizing mechanism. In these figures, A indicates the three conductors of a three-phase system; B, oil-wells; C, bridge-rods, each coacting with two oil-wells; D, source of constant current; E, electromechanical hand-switch, located at a distance from the oil-wells; F, contact-arm of hand-switch; G G', actuating-magnets, located at the oil-wells, for raising and lowering the bridge-pieces and for moving the switch-levers H H'. In Fig. 1 of the diagram the parts are shown in the position which they would occupy with the bridge-rods elevated and the circuits through the oil-wells broken. It will be observed that the contact-arm of the hand-switch E at this time occupies a midway position and that the switch-lever H' covers the contacts I' of the actuating mechanism located at the right. In Fig. 2 the contact-arm F of the hand-switch E is shown as thrown to the left and the switch-levers H H', respectively covering the contacts I I', at the right and left of the mechanism and that the bridge-rods are half-way in the oil-wells. In Fig. 3 the contact-arm is supposed to be thrown to the left, with the contact-levers H H' both thrown to the left and with the contact-lever H covering the contacts I, and were this figure extended it would show the bridge-rods as fully inserted within the oil-wells and in electrical contact.

with the contact devices contained within the oil-wells.

The operation of the device, so far as relates to the action of the hand-switch upon the actuating mechanism and the actuating mechanism upon the hand-switch, is as follows: Assuming the contact-arm F of the hand-switch E to be thrown to the left—i. e., into the position shown in Fig. 2—a current will flow from dynamo D through conductor J, magnet K, magnet G, conductor M, contacts I', conductor N, back to dynamo. The pull of the solenoid K, acting through its core, will maintain the contact-arm of the hand-switch in the position shown in Fig. 2 until the switch-levers H H' have been pulled by the solenoid G, acting through its core O, to the left-hand position—i. e., into the position shown in Fig. 3. As soon as the switch-lever H' leaves the contacts on the right the circuit will be broken through solenoid K, at which time the contact-arm of the hand-switch E will, under the action of a suitable spring L, return to its initial position—i. e., to that shown in Fig. 1. When next it is desired to open the circuit, the hand-switch E is pulled to the right, which reverses the operation. In practice I prefer that the relation of the parts shall be such that the magnets in the hand-switch shall be deenergized slightly before the movement of the oil-switch, excited by the hand-switch, has been completed—i. e., just before the contact is made or broken. I take this course as a measure of protection, although I do not consider it essential.

Referring now to the construction of the oil-switch, 1 indicates a vault or receptacle in which the oil-wells are located. This receptacle, which is suitably inclosed at the top and bottom, is divided into a series of chambers 1^a 1^b 1^c by insulating-partitions 2, of brick or other suitable material, and is provided on the front with suitable doors 3. I prefer to make the doors in two parts secured together at their center by means of a button 4 or other device, as shown. The doors, however, may be otherwise arranged. Located within each chamber are two oil-wells B. The construction of the oil-wells is best shown in Fig. 8, each of which consists of an outer casing 5, with an insulating-lining 6, which may be made either of fiber or of a vitreous material, as desired. Located above the lining 6 is a washer 7, and mounted upon the washer is a porcelain insulator 8, provided with a circumferential supporting-flange 9. Located over the flange 9 is a second washer 10, and, finally, over this washer a cap or cover 11, secured to the casing 5 by means of a screw-thread. The supporting-flange of the insulator 8 is provided with the radial grooves 12 to provide openings through which the oil contained within the casing when expanded by heat may rise into the cavity of the cap 11 and when the heat has been dissipated flow back

again into the casing or when subjected to a disruptive discharge, owing to the formation of an excessive arc, may be carried entirely out of the casing. Located within the insulator 8 is a guide-tube 13, secured therein by means of washers 14. The upper end of the tube 13 has formed on it a screw-thread 15, over which is applied an annular guide-cap 16, which I prefer to make of steel or other refractory material that will not be worn by the reciprocations of the bridge-rod working through it. In Fig. 9 I have shown the guide-cap 16 detached from the guide-tube 13 and held by means of springs 17, secured to the bridge-rod C, the object of which arrangement is to prevent the cap 16 from being lost when it is unscrewed from the tube 13 and to permit the removal of an oil-well from a chamber of the vault or receptacle without the necessity of the attendant touching any part of the switch mechanism. Connected to the bottom of the casing 5 is a base-piece 18, supported in an insulator 19, which corresponds in shape to the insulator 8. The base-piece 18 is recessed on its interior to form an annular threaded chamber 20. Situated within this chamber is an annular ring 21, to which is secured four pairs of contact-strips 22 23. These strips are formed of good conducting material and have flat surfaces, so as to bear upon the sides of the bridge-rods C, which are made square. The annular ring 21 is held in position by means of the threaded ring 24. Carried at the upper end of the contact-strips 23 are the brass contact-blocks 25, secured in position by means of screws 26. These blocks may be readily removed by releasing the screws when it is desired to insert a new contact-block in case one should be injured. In the practical operation of the device the arcing always takes place between the bridge-rod C and this block, which thus serves to protect the contact-strips 22 23. Located below the annular chamber 20 is a second annular chamber 27, within which is located an annular plate 28. Located below the plate is a helical spring 29. The function of the plate and spring is to overcome the friction exerted by the contact-strips 22 23 on the bridge-rod C, and thus facilitate the opening of the switch. 30 indicates a conductor secured at one end to the bottom of the oil-well and at the opposite end to one terminal of a conductor A of the main circuit.

I will now describe the means by which the oil-wells (two for each conductor) are supported within a chamber of the vault or receptacle and how these oil-wells may be readily removed from the vault for inspection and repair.

Located within each one of the receptacles 1^a 1^b 1^c is a platform 31, which platform is carried by four pivoted links 32. Projecting from the back of the platform is a stop 33, which limits the inward movement of the plat-

form, and projecting upward from the bottom of the receptacle is a stop 34, which limits the downward and outward movement of the platform. The front of the platform is 5 provided with a pivoted arm 35, Fig. 7, in which is formed an eye 36, Fig. 5. When it is desired to examine the oil-wells B, a hook is caught in the eye 36 of the pivoted arm 35, and the platform 31 and oil-wells are drawn 10 forward to the position shown in the dotted lines. The arrangement described is one which has been found very convenient in practice; but I do not wish to limit myself to the precise construction described, as it will be 15 within the intent of my invention to mount the oil-wells upon any suitable platform or in any suitable manner within the inclosing chambers.

Secured to the lower end of the conductor 20 30, below the table 31, is a pivoted switch-blade 37, which is adapted to coact with the spring-clips 38 on the end of a conductor A. The conductor A is shown as mounted in an insulator 39. The switch 37 is not an essential 25 part of my device; but I find it convenient for use after the main contacts in the oil-wells have been separated, as it insures the breaking of the circuit, and thus in a measure gives confidence against accidents to the 30 workman who must examine or repair the switch. I wish it understood that I do not intend to use this switch in any wise as a means for breaking the main circuit in the ordinary operation of the device. Contact with the 35 opposite oil-well is made through a contact-plate 40, which coacts with clips 41, carried by a conductor A, mounted in the insulator 42. I do not wish to limit myself in any wise to the means described for connecting the oil-wells to the main circuit-conductors, as other 40 means than those shown may be employed.

I will now describe the device employed for elevating and lowering the bridge-rods C. Each pair of rods is connected together by 45 means of a conducting cross-head 43, and to each of these cross-heads is connected a wooden rod 44, which are united at the top by means of a cross-head 45, Fig. 4. This cross-head is connected to a tube 46, which moves on a 50 vertical rod 47, forming a part of a standard 50, mounted on top of the vault or receptacle.

It will be understood from the description so far as given that the bridge-rods C and cross-head 43 form, in fact, a bridge between 55 the ends A A of a conductor and that therefore the making and breaking of a circuit traversing a conductor of a system is wholly within one chamber of the receptacle, and, further, that if simultaneous movement is 60 given to all of the bridge-rods the making and breaking of all of the circuits (in the present case three) will occur at the same time.

Arranged transversely of the standard 50 is a shaft 51, Fig. 17, and on the inner end of

this shaft is loosely pivoted a lever 52. The 65 lever 52 is connected through the pivoted link 53 with the cross-head 45. Thus it will be seen that when the lever 52 is rotated the cross-head 45 will be elevated or depressed in accordance with the movement of the lever. 70 Mounted upon the other end of the shaft 51 and occupying a position at one hundred and eighty degrees from that occupied by the lever 52 is a lever 54. Secured at one end to this lever and on the other end to the frame 50 is 75 a helical spring 55, the object of which arrangement is to counterbalance the weight of the lever 52, link 53, cross-head 45, rods 44, cross-head 43, and bridge-rods C, and thus promote ease of movement of the parts. Figs. 80 5 and 17 respectively show the position of the parts when the switch is closed and open. Mounted also upon the shaft 51 is a lever 56. This lever is fixed to the shaft 51 and is provided with a pair of rearwardly-extending 85 arms 57, which embrace the lever 52. The arms 57 of the lever 56 are separated for a distance somewhat greater than the width of the lever 52. Consequently when the lever 56 is set in motion the arms 57 will impart to the lever 52, 90 which is loose on the shaft 51, first, a hammer-blow, then a continuous push, until the limit of the travel of the lever 56 has been reached. The lever 52 is permitted to travel through one hundred and eighty degrees and the lever 56 95 through a slightly-greater distance, when further motion will be arrested by reason of the spring-stops 58 projecting from the frame 50. Mounted also upon the shaft 51 is a band-wheel 59, and secured to this wheel is a band 100 60. The band may be secured by means of a screw 61 or otherwise. All that is required is that the band shall be so fastened as not to slip upon the wheel. Connected to the ends 105 of band 60 are the cores O O' of the solenoids G G'. Situated under each solenoid is a dash-pot 62, which may be of any suitable construction. Preferably, however, the dash-pot consists of a casing 63, in which is a leather piston 64, located between metallic disks 65. 110 These disks are connected through the rods 66 with a plate 67, in which is an opening 68 for the rod 69. The rod 69 is connected to the bottom of a core and is surrounded by a sleeve 70. Located on the rod 69 is a nut 71, 115 the purpose of which is to determine by moving this nut up along the rod 69 the moment when the dash-pot shall be thrown into operation in the upward movement of the core. The dash-pot is thrown into operation on the 120 downward movement of the core by the end of the sleeve 70 striking the plate 67.

72 represents a valve in the dash-pot, which in the present case consists of a ball and suitable seat. This arrangement of ball and seat 125 prevents the entrance of air in the upward movement of the piston, but permits the entrance of air on the downward movement of

the piston. The chief object of the dash-pot is to cushion the movement of the operating parts of the switch-actuating mechanism.

On the end of the rod 69 is an eye 73, by 5 means of which an operator with a hook may open the switch from the outside of the receptacle.

I will now describe the mechanism by reason of which the actuating-solenoid, as also the 10 solenoid which at the time controls the hand-switch, are deenergized just before the switch mechanism has completed its movement of one hundred and eighty degrees, or, in other words, just before the switch mechanism has 15 closed the circuit through the switch or opened the circuits through the switch.

Located on the shaft 51 and back of the band-wheel 59 or forming a part of the band-wheel is a cam-wheel 80, having formed in 20 its rear surface a cam-slot 81. This slot is open at the center 82 and communicates with the periphery of the cam-wheel and is normally closed at the ends by the springs 83, which are secured to the body of the cam- 25 wheel at 84 and are free to be moved outward at 85. The cam-wheel 80 moves coincidently with the wheel 59. Coacting with the cam-wheel 80 are the pivoted levers H H', respectively carrying the projecting pins 86 86^a.

30 In Fig. 13 the pin 86 is shown as resting upon the eccentric surface of the cam-slot and the pin 86^a upon the periphery of the cam-wheel. Mounted upon the upper end of the levers H H' are the bridge-pieces 87 87^a. These bridge-pieces are arranged to bridge the contacts II'. In Figs. 1, 2, and 3 the various positions which the levers H H' will take upon the rotation 35 of the cam-wheel will be seen. In Fig. 1 the pin 86 is in the cam-slot and bears upon the eccentric surface of the cam-slot, and the pin 86^a is located external to the cam-wheel and bears upon its periphery. In Fig. 2 the pins 86 86^a both bear upon the periphery of the cam-wheel, the pin 86, owing to the rotation 40 of the cam to the left, having moved out of the cam-slot and its movement raised the upper spring 83 and passed out from under the spring. In Fig. 3 the pin 86^a has dropped into the cam-slot through the opening 82 and 45 bears upon the eccentric surface of the cam-slot and the pin 86 is external to the cam-wheel and bears upon its periphery. The position of the pins 86 86^a relative to the cam-wheel and cam-slot, as described, are those 50 which take place when the cam-wheel is rotated to the left. Corresponding positions in reverse order will be taken by such pins when the cam-wheel is moved to the right.

In order to prevent the possible operation 60 of the switch by means of a jar, I provide means for locking the levers 56 52. Projecting forwardly from the lever 52 is a pin 88, and situated on the back of the supporting-plate 89 is a pivoted latch 90. Over the rear

end of the latch is a stop 91 and over the front 65 end a spring 92. The forward end of this latch is provided with a projecting pin 93, which coacts with the lever 56. A corresponding latch 94 is shown in the bottom of Fig. 13.

95 represents buffers in the path of movement of the levers H H'; 96, a spring which connects the levers H H'.

The operation of this portion of the device is as follows: When a current is sent through one or the other of the magnets G G', a core 75 O is attracted. The movement of the core transmitted to the band 60 rotates the shaft 51. This movement is transmitted to the lever 56, which moving its top cam-surface under the pin 93 of the latch 90 raises the latch out of 80 the path of movement of the pin 88 on the lever 52. The lever 56 then imparts a blow to the lever 52 and pushes it continuously forward and to the left until both levers have traversed one hundred and eighty degrees, at 85 which point the pin 88 is caught by the latch 94 and the levers H H' will have moved to the position shown in Fig. 3 of the drawings.

I wish it understood that I do not limit myself to the specific mechanism described for 90 altering the circuit connections to the actuating solenoids or the solenoids at the hand-switch, as many changes may be made in this portion of the apparatus without departing from the intent of my invention.

Having thus described my invention, I 95 claim—

1. An electric switch, comprising an insulated chamber, a pivoted platform in said chamber, and an oil-well mounted on the platform.

2. An electric switch comprising an insulated chamber, a pivoted platform, an insulator mounted on the platform, and an oil-well mounted on the insulator.

3. An electric switch, comprising in its construction an insulated chamber, a pivoted platform, an oil-well mounted on said platform, and means for connecting said oil-well to the terminals of an electrical conductor.

4. An electric switch comprising in its construction an insulated chamber, a pair of insulated terminals projecting into said chamber, a pivoted platform, a pair of oil-wells mounted on said platform, and means for establishing electrical connection between the oil-wells and the terminals.

5. An electric switch, comprising in its construction an insulated chamber, a pair of insulated terminals projecting into said chamber, spring-clips on the end of said terminals, a pivoted platform, a pair of oil-wells mounted on said platform, and mechanism connected to the oil-wells for establishing electrical connection between the oil-wells and the terminals.

6. An electric switch comprising in its construction an insulated chamber, a platform,

- 10 pivoted links introduced between such platform and chamber, and a pivoted eye connected to said platform.
- 15 7. An electric switch comprising in its construction, a vault or receptacle divided into a number of separated and insulated chambers, a pivoted platform in each chamber, and mechanism for making and breaking circuits mounted on said platform.
- 20 8. An electric switch comprising in its construction, a vault or receptacle divided into a number of separated and insulated chambers, a pivoted platform in each chamber, and a pair of oil-wells mounted on each platform.
- 25 9. An electric switch comprising in its construction, a vault or receptacle divided into a number of separated and insulated chambers, a pivoted platform in each chamber, a pair of oil-wells carried on insulators on each platform, and
- 30 means for connecting said oil-wells to the terminals of an electrical conductor.
- 35 10. An electric switch comprising in its construction, a vault or receptacle divided into a number of separated and insulated chambers, a pivoted platform in each chamber, a pair of oil-wells mounted on each platform, means for connecting one oil-well of a pair with one terminal of a conductor, and a line-switch interposed between the other oil-well of the pair
- 40 and the other terminal of the conductor.
- 45 11. An electric switch comprising in its construction, an oil-well having an inclosing casing, an insulating-lining, an insulator having openings in its body mounted in the top of the casing, an annular cap located over the insulator, a series of spring-contacts mounted in the lower portion of the casing, and contact-blocks carried by said spring-contacts.
- 50 12. An electric switch comprising in its construction, an oil-well having an inclosing casing, an insulating-lining, an insulator provided with a supporting-flange having openings therein mounted in the top of the casing, a guide-tube carried by said insulator, a series of spring-contacts mounted in the lower portion of the casing, contact-blocks carried by said spring-contacts, and a reciprocating bridge-rod coacting with said spring-contacts and contact-blocks.
- 55 13. An electric switch, comprising in its construction an oil-well having an inclosed casing, an insulating-lining, an insulator provided with a flange having openings therein mounted in the top of the casing, a guide-tube carried by the insulator, a guide-cap mounted on the guide-tube, a series of spring-contacts located in the lower portion of the casing, contact-blocks carried by said spring-contacts, and a reciprocating bridge-rod adapted
- 60 to coact with said spring-contacts and contact-blocks.
- 65 14. An electric switch comprising in its construction an oil-well having an inclosing casing, a series of spring-contacts mounted in the lower portion of the casing, a reciprocating bridge-rod which coacts with said contacts, and a spring-pressed plate which coacts with said bridge-rod to overcome the friction of the spring-contacts.
- 70 15. An electric switch comprising in its construction an oil-well, a guide-cap mounted on the top of the oil-well, a reciprocating bridge-rod, a pair of springs carried by said bridge-rod and adapted to coact with said guide-cap when it is removed from the oil-well.
- 75 16. An electric switch comprising in its construction, a vault or receptacle divided into a number of separated and insulated chambers, a pivoted platform in each chamber, a pair of oil-wells carried on insulators on each platform, and a pivoted link connected to each platform by means of which the platforms may be drawn out of the chambers.
- 80 17. An electric switch comprising in its construction, a vault or receptacle divided into a number of separated and insulated chambers, a pivoted platform in each chamber, a pair of oil-wells carried on insulators on each platform, a pivoted link connected to each platform by means of which the platforms may be drawn out of the chambers, and means for limiting the inward and outward movement of the platforms.
- 85 18. In combination with the bridging devices of an oil-switch, means for imparting motion to said bridging devices, said means consisting of a pair of solenoidal magnets, a horizontally-disposed shaft adapted to be rotated in one direction or the other as one or the other of the magnets is energized, means for shifting the path for the current through said solenoids, and means for shifting the position of the current-controlling device from an operative to a neutral position when the movement of the bridging devices in either direction to open or close the switch has been reached.
- 90 19. In combination with the bridging device of an oil-switch, of means for imparting motion to said bridging device, said means consisting of a pair of solenoidal magnets, a horizontally-disposed shaft adapted to be rotated in one direction or the other as one or the other of the magnets is energized, a lever carried by said shaft, a second lever connected to the bridging device and adapted to be struck a hammer-blow and rotated in one direction or the other when the first-named lever is moved.
- 95 20. In combination with the actuating mechanism for the bridging devices of an oil-switch, an independent source of energy, a hand-operated switch, solenoids which serve to hold the switch in fixed positions until deenergized, and means operated by the actuating mechanism for deenergizing the solenoids of the hand-switch.
- 100 21. In combination with the actuating mech-

anism for the bridging device of an oil-switch, an independent source of energy, a hand-switch, solenoids which serve to hold the switch in fixed positions until deenergized, and a pair 5 of levers moved by the actuating mechanism and which will alternately break and close circuits through the solenoids of the hand-switch.

22. In combination with the bridging devices of an oil-switch, means for counterbalancing the weight of the bridging devices, 10 means for reciprocating the bridging devices, and means for imparting to the reciprocating means a hammer-blow when starting, to overcome the inertia and frictional resistance of 15 the bridging devices against movement.

23. In combination with the bridging devices of an oil-switch, of actuating mechanism therefor, said actuating mechanism consisting of a horizontal shaft, a band-wheel on the end 20 of the shaft, a band over said band-wheel, a pair of magnets having their cores attached to the ends of the band, a lever attached to said shaft, and a second lever loosely pivoted on 25 said shaft and connected to the bridging devices.

24. In an oil-switch and in combination with the mechanism for reciprocating the bridging devices of said switch, a horizontal shaft to which motion is imparted alternately in opposite directions by a pair of magnets, a cam-wheel mounted on said shaft, a pair of levers 30 adapted to coact with said cam-wheel, and contacts in circuit with a source of energy adapted to be bridged by the said levers.

35 25. In combination with the actuating

mechanism for the bridging devices of an oil-switch, of means for limiting the movement of said actuating mechanism after the determined range of movement has been ended, such means consisting of latches adapted to coact 40 with the lever which raises and lowers the bridging devices and with the lever which imparts movement to such first-named lever.

26. In combination with the actuating mechanism for the bridging devices of an oil-switch, a cam-wheel having a cam-slot formed 45 in one face, and means consisting of levers having projecting pins which coact with said cam-slot to alternately reverse the circuit connections to the actuating mechanism. 50

27. In combination with the mechanism for reciprocating the bridging devices of an oil-switch, a horizontal shaft, means for producing rotative movement of said shaft alternately in opposite directions, a cam-wheel 55 mounted on said shaft, said cam-wheel provided with a cam-slot open at the center and covered at the ends by a pair of springs, a pair of levers provided with pins which move in said cam-slot, and bridging contacts carried by said levers and adapted when the cam is rotated to alternately close and open circuits through said means for producing rotative movement of the shaft.

In testimony whereof I affix my signature in 65 the presence of two witnesses.

HENRY PRICE BALL.

Witnesses:

J. E. PEARSON,
C. E. STECHER.
